COMBINED CUSHION AND HEAD REST

John Malouf, 420 N. Lee St., Altus, Okla., assignor of
one-half to Philip Malouf, Santa Monica, Calif.

Filed Apr. 18, 1962, Ser. No. 69,761

Term of patent 7 years

(Cl. D15—8)

FIG. 1

FIG. 2

FIGURE 1 is an elevational view of my new design for a combined cushion and head rest.

FIGURE 2 is a front elevational view.

The appearance of the back is the same as the front.
I claim:

The ornamental design of a combined cushion and head rest, as shown and described.
